(57) **CLAIM**

The ornamental design for a wipe dispenser frame, as shown and described.

DESCRIPTION

FIG. 1 is a first perspective view wipe dispenser frame showing our new design;

FIG. 2 is a second perspective view thereof;

FIG. 3 is a front elevational view thereof;

FIG. 4 is a rear elevational view thereof;

FIG. 5 is a first side elevational view thereof;

FIG. 6 is second side elevational view thereof;

FIG. 7 is a bottom plan view thereof; and,

FIG. 8 is a top plan view thereof.

The broken lines in the drawings depict unclaimed subject matter only and form no part of the claimed design.
